UNITED STATES PATENT OFFICE.

WILLIAM S. ELTERS, OF DAYTON, OHIO, ASSIGNOR TO THE GEM CITY SHEET METAL CO., OF DAYTON, OHIO, A CORPORATION OF OHIO.

DESIGN FOR A HOOD FOR REGISTERS.

Application filed December 7, 1926. Serial No. 19,960. Term of patent 14 years.

To all whom it may concern:

Be it known that I, WILLIAM S. ELTERS, a citizen of the United States, and resident of Dayton, county of Montgomery, State of Ohio, have invented a new, original, and ornamental Design for Hood for Registers, of which the following is a specification, reference being had to the accompanying drawing, forming a part hereof.

Fig. 1 is a perspective view and Fig. 2 is an end view of a hood for registers showing my new design.

I claim:

The ornamental design for a hood for registers, substantially as shown.

In testimony whereof, I have hereunto set my hand this 27th day of November, 1926.

WILLIAM S. ELTERS.
